NAMEPLATE

Alvin Seyler, Vintage St., Campbell City (or P.O. Box 428), Kissimmee, Fla. 32741

Filed Nov. 8, 1973, Ser. No. 413,838

Term of patent 14 years

Int. Cl. D20—03

U.S. Cl. D96—12 F

Fig. 1.

Fig. 2.

Fig. 3.

FIG. 1 is a perspective view of a nameplate showing my new design;

FIG. 2 is a front elevational thereof; and

FIG. 3 is an end elevational view thereof.

The rear of the center plate is identical to the front except without the scroll work.

I claim:

The ornamental design for a nameplate, substantially as shown and described.
